UNITED STATES PATENT OFFICE.

WILLIAM BURRELL, THOMAS ROHANN, AND FRANK A. FLETCHER, OF
MINNEAPOLIS, MINNESOTA.

ADJUSTABLE HARNESS-SADDLE PAD.

SPECIFICATION forming part of Letters Patent No. 236,303, dated January 4, 1881.

Application filed May 26, 1880. (Model.)

To all whom it may concern:

Be it known that we, WILLIAM BURRELL, THOMAS ROHANN, and FRANK A. FLETCHER, all of Minneapolis, in the county of Hennepin and State of Minnesota, have invented a new and valuable Improvement in Adjustable Harness-Saddle Pads; and we do hereby declare that the following is a full, clear, and exact description of the construction and operation 10 of the same, reference being had to the annexed drawings, making a part of this specification, and to the letters and figures of reference marked thereon.

Figure 1 of the drawings is a representation 15 of an edge view of our improved harness-pad, and Fig. 2 is a top view thereof.

This invention has relation to improvements in saddle-pads for single or double harness.

The object of the invention is principally to 20 devise means in harness-saddles whereby the bearing-surfaces of the pad may be shifted in the event of the formation of a sore upon an animal's back, so as to press upon a part away from the sore and give it a chance to heal up; 25 and it consists in a pad having transverse end loops, and a female-threaded eyelet between said loop, and adjustably secured to the backing of the pad, as hereinafter shown and described.

30 In the annexed drawings, the letter A designates the tree or support of our improved harness-saddle, designed to rest across a horse's back and serving as a foundation for the saddle proper, which carries the check-rein hook.

35 B indicates the pads, composed usually of a backing, *a*, and a stuffed cushion, *b*, and preferably of oblong form. This pad has at its upper end a raised loop, *e''*, through which the end of the support A is passed, and at the 40 other a second loop, *d*, formed by means of a strap, *d'*, having a buckle, *e*, and billet *e'* at one end for the reception of its other end.

This strap has a metallic backing, *f*, which holds the loop in fixed form, the said loop being for the purpose of receiving the flap or 45 strap of the harness-saddle. The pad is provided at its middle portion with a female-threaded eyelet, *g*, let in or otherwise secured to the backing *a*, and is attached to the ends of the support A by means of a screw, *S*, extending through a perforation, *i*, in the said support into the eyelet of the pad, as shown in Fig. 1.

There are several perforations, *i*, in each end of the pad-support A, arranged at suitable distances apart, by means of which the pad may be adjusted up or down, as may be required to prevent it from bearing upon and irritating a sore or spot inclined to become sore.

The arrangement of the loops *e'' d*, the one 60 receiving the pad-support and the other flaps of the saddle, prevents the pads from becoming displaced relative to the support and saddle flaps or straps, and thus prevents undue rubbing, and the metallic backing of the latter 65 loop, *d*, protects it from sliding out on either side from under the saddle. The pads for double harness are applied by means of two screws.

What we claim as new, and desire to secure 70 by Letters Patent, is—

The pad B, having the transverse end loops, *e'' d*, and a female-threaded eyelet, *g*, between said loops, and adjustably secured to the backing of the pad, substantially as specified.

In testimony that we claim the above we have hereunto subscribed our names in the presence of two witnesses.

WILLIAM BURRELL.
THOMAS ROHANN.
FRANK A. FLETCHER.
